DIFFUSER GRILLE

Ernest Hjalmar Person, New Britain, Conn., assignor to
Allied Thermal Corporation, New Britain, Conn., a cor-
poration of Connecticut

Filed Dec. 13, 1963, Ser. No. 77,788

Term of patent 14 years

(Cl. D62—4)

FIG. 1

FIG. 2

FIG. 3

FIG. 4

FIG. 5

FIG. 1 is a front elevational view of a diffuser grille embodying my new design;

FIG. 2 is an enlarged, fragmentary isometric view of one of the grille bar elements;

FIG. 3 is a cross-sectional view taken along the line 3—3 of FIG. 4;

FIG. 4 is an enlarged, fragmentary rear elevational view of one of the grille bar elements shown in FIG. 1;

FIG. 5 is a front elevational view similar to FIG. 1 but showing a modified diffuser grille embodying my new design.

The conventional frame member shown in broken lines in the drawing is of conventional thickness.

The dominant features of my design reside in the full line portions of the drawings.

This application is a continuation-in-part of my co-pending application Serial No. D. 73,467, filed February 6, 1963 and now abandoned.

I claim:

The ornamental design for a diffuser grille, as shown and described.
